United States Patent Office

Des. 187,782
Patented May 3, 1960

187,782

SUCTION CLEANER

Clarence E. Stevens, Pasadena, Calif., assignor to The Filtex Corporation, Los Angeles, Calif., a corporation of Michigan

Application September 15, 1958, Serial No. 52,646

Term of patent 14 years

(Cl. D9—2)

FIG. 1.

FIG. 2.

Figure 1 is a top plan view of a suction cleaner embodying the new design; and

Figure 2 is an elevational view thereof as seen from the right of Figure 1.

I claim:

The ornamental design for a suction cleaner, as shown.
